Inventor:
John G. Perry

UNITED STATES PATENT OFFICE.

JOHN G. PERRY, OF KINGSTON, RHODE ISLAND.

SAUSAGE-STUFFER.

Specification of Letters Patent No. 25,440, dated September 13, 1859.

To all whom it may concern:

Be it known that I, JOHN G. PERRY, of Kingston, in the county of Washington, in the State of Rhode Island, have invented a 5 new and useful Improved Machine for Filling Sausages; and I do hereby declare that the following is a full and correct description thereof, reference being had to the accompanying drawings and to letters of reference marked thereon, similar letters in the different figures denoting the same parts.

In these drawings Figure 1 is a perspective view of the machine open to show the internal arrangement. Fig. 2 is a view in 15 perspective of the machine closed ready for operating.

The distinctive feature of my machine, in which it differs from others made for the same purpose consists mainly in using a cylinder having a special cavity in its periphery in combination with a nozzle or nozzles and a follower or leaf-cam fitted into and working in this cavity, so that by their combined action the meat is forced out the nozzle into the cases.

To enable others skilled in making machinery to construct my machine I will describe its different parts and mode of operation.

30 The case A is a hollow cylinder divided horizontally through its center into an upper and lower part, which are hinged together on one side and provided with a fastening *a* upon the other side to keep it closed 35 while in operation. On both the upper and lower parts of the case A are made flat semicircular projections B B (square to the plane of revolution of the cylinder C) which when the two parts of the case are 40 shut together, form, by means of a slight projecting ridge on each, a chamber to hold the follower or leaf cam D.

C is a cylinder with a spiral hollow made in its surface, into which is fitted the leaves 45 of the follower or cam D which may be made with two or more leaves and is pivoted at its center on a stud or screw-pin *d*, which passes through the center of the projection B. The cylinder C has a shaft E projecting 50 at one end upon which it turns in a bearing F at the end of the case opposite to the dis-

charging orifice or orifices. Upon the outer end *e* of this shaft is placed the crank or pulley for communicating motion to the cylinder the other end of which may or may not 55 have a journal at its center to turn on, as it is not necessary that it should, because the body of the cylinder turning in the case will keep it in place and steady.

G are the discharging tubes or nozzles 60 which hold the bags or cases that are to receive the meat; there may be one or more of these nozzles and they may be placed directly in the end, or in the side of the case A.

H is a hopper for receiving the meat into 65 the machine.

The operation of the filler is as follows: Motion being given to the spiral cylinder C the meat is steadily fed in through the hopper without having to stop and reverse the 70 motion as is necessary in loading others, and is received into the spiral cavity of C and is carried around with it until it comes in contact with the leaf of the follower, when being prevented from going around any farther with the cylinder it is compelled by the combined action of the cylinder and follower to pass forward to the end of the machine and out of the nozzles into the cases that are placed on them, and so continually fills and 75 delivers the sausages from the nozzles into the receiver below. If it were not for the obstruction offered by the follower or leaves D the meat would have too great a tendency 80 to continue turning around with the cylinder instead of being forced toward the end of the machine. The follower and spiral cavity are so adapted to each other that as one leaf is forced out by the action of the cylinder, another leaf is carried in so that 85 there is one filling a horizontal section of the cavity at all times.

I claim—

Combining the cylinder C, having a spiral cavity, or cavities, with the follower D, substantially as described, for the purposes 95 herein set forth.

JOHN G. PERRY.
